[57] CLAIM

The ornamental design for a combined carrying and storage case for art supplies, as shown and described.

DESCRIPTION

FIG. 1 is a perspective view of a combined carrying and storage case for art supplies showing my new design, in a fully open condition;

FIG. 2 is a top plan view thereof;

FIG. 3 is a front elevational view thereof;

FIG. 4 is a left side elevational view thereof;

FIG. 5 is a bottom plan view; and

FIG. 6 is a rear elevational view.
